UNITED STATES PATENT OFFICE.

SAMUEL G. GOSS, OF CHICAGO, ILLINOIS, ASSIGNOR TO THE GOSS PRINTING PRESS COMPANY, OF SAME PLACE.

DELIVERY APPARATUS FOR PRESSES.

SPECIFICATION forming part of Letters Patent No. 666,751, dated January 29, 1901.

Application filed November 29, 1897. Serial No. 660,050. (No model.)

To all whom it may concern:

Be it known that I, SAMUEL G. GOSS, a citizen of the United States, residing in Chicago, in the county of Cook and State of Illinois, have invented certain new and useful Improvements in Delivery Apparatus for Presses, of which the following is a specification.

My invention relates particularly to delivery apparatus for printing-presses, although it may be used in connection with other machinery acting upon a web of paper or other material.

It has for its object to provide improved delivery mechanism by the use of which the drawing grip will be applied to the web along separated lines, so that the greater part of the surface of the web, and particularly the printed part, will not be gripped to any material extent by the delivery devices, which construction is of special utility in connection with printing machinery, as the printed surfaces of the web are not offset, smeared, or otherwise damaged, as is frequently the case where the entire surfaces of the web are gripped tightly by the delivery devices.

To this end my invention consists of a feeding-roll for paper-feeding machines having a series of projecting springs, (metallic or otherwise,) said springs being annularly arranged and presenting yielding bearing-surfaces.

It further consists in a pair of coacting rolls provided with gripping devices consisting of a series of projecting springs (metallic or otherwise) annularly arranged on one or both of said rolls.

It further consists in providing said rolls with a plurality of said gripping devices arranged a suitable distance apart.

My invention also consists in a web-feeding device, consisting of a pair of coacting rolls provided with a plurality of elastic metallic gripping devices which grip the web sufficiently to draw it, and in certain other specific details, which will be hereinafter pointed out.

In the accompanying drawings, Figure 1 is a view of a portion of the former in combination with my improved delivery-rolls. Fig. 2 is a side elevation of the same, and Fig. 3 is a plan view of the delivery-rolls.

4 indicates the former, which is suitably mounted.

5 indicates the frame of the delivery apparatus, and 6 7 indicate shafts suitably mounted thereupon at opposite sides of the apex of the former. The shaft 6 is mounted in blocks 8, which are adjustable in boxes 9, as shown in Figs. 1 and 3, so that they may be adjusted when necessary.

10 indicates adjusting-screws.

11 12 indicate rolls which are mounted on the shafts 6 7, respectively. The rolls 11 12 are so placed that they are not close enough to each other to have a drawing grip upon the web.

At its ends the roll 11 is provided with gripping-springs 13, which are curved at their ends and overlap, as illustrated in Fig. 1. 14 indicates similar springs which are provided at the ends of the roll 12 and are arranged reversely to the springs 13.

The springs 13 14 project beyond the surfaces of their respective rolls, and the opposite springs 13 14 engage each other, thus forming, in effect, depressed portions between the ends of the rolls.

The length of each roll between its spring-grippers is equal to the width or length of a printed page, as the case may be, so that the springs engage the web along the line of the longitudinal margins of the pages, as illustrated in Figs. 1 and 2.

By this construction the printed portion of the web is not materially engaged, pressed, or rubbed by the surfaces of the rolls, the only points at which the webs are tightly gripped being along unprinted margins, thus all danger of damage to the printed part being avoided.

In practice the rolls 11 12 are driven at a slightly-greater speed than that of the web, so that the web is kept taut and prevented from wrinkling.

The grip of the spring-grippers upon the web may be increased or diminished by adjusting the roll 11 by means of the adjusting apparatus above described.

Although I have described my invention in detail, I do not wish to be limited to the specific construction herein shown and described, as various modifications may be made without departing from my invention.

That which I claim as my invention, and desire to secure by Letters Patent, is—

1. A web-feeding device consisting of a pair of coacting rolls provided with a plurality of elastic metallic gripping devices, substantially as described.
- 5 2. A web-feeding device consisting of a pair of coacting rolls provided with gripping devices consisting of a series of projecting springs annularly arranged on one or both of said rolls, substantially as described.
- 10 3. A web-feeding device consisting of a pair of coacting rolls provided with a gripping device at each end, said gripping device consisting of a series of overlapping springs, substantially as described.
- 15 4. A feeding - roll for paper - feeding machines having a series of projecting springs thereon, said springs being annularly arranged and presenting yielding bearing-surfaces, substantially as and for the purpose described.
- 20 5. A feeding - roll for paper - feeding machines having a series of projecting overlap-
- ping springs thereon, said springs being annularly arranged and presenting yielding bearing-surfaces, substantially as and for the purpose described.
6. The combination with a longitudinal folder, of a pair of coacting rolls arranged below the apex of said folder, said rolls being provided with web-gripping devices at each end, each of said gripping devices consisting of a series of overlapping springs, substantially as described.
7. A web-feeding device consisting of a pair of coacting rolls provided with a gripping device at each end, said gripping device consisting of a series of springs annularly arranged and presenting yielding bearing-surfaces, substantially as described.

SAMUEL G. GOSS.
